DESIGN FOR A FOUNTAIN STENCIL BRUSH

Otto J. Herb, St. Louis, Mo., assignor to Dia-graph-Bradley Stencil Machine Corporation, St. Louis, Mo., a corporation of Missouri

Application December 18, 1943, Serial No. 112,030

Term of patent 14 years

(Cl. D9—2)

To all whom it may concern:

Be it known that I, Otto J. Herb, a citizen of the United States and a resident of St. Louis, Missouri, have invented a new, original, and ornamental Design for a Fountain Stencil Brush, of which the following is a specification, reference being had to the accompanying drawing, forming part thereof, in which

Fig. 1 is a top plan view of a fountain stencil brush showing my new design;

Fig. 2 is a front elevation thereof; and

Fig. 3 is a bottom plan view thereof.

I claim:

The ornamental design for a fountain stencil brush, as shown.

OTTO J. HERB.
